UNITED STATES PATENT OFFICE.

LORENZ KILLIAN, OF BROOKLYN, NEW YORK, ASSIGNOR TO PALMER & EMBURY MFG. CO., OF NEW YORK, N. Y., A CORPORATION OF NEW JERSEY.

DESIGN FOR A CHAIR.

No. 39,845.

Specification for Design.

Patented Feb. 23, 1909.

Application filed May 12, 1908. Serial No. 432,539. Term of patent 7 years.

To all whom it may concern:

Be it known that I, LORENZ KILLIAN, a citizen of the United States, residing in the city of Brooklyn, in the county of Kings and State of New York, have invented a new, original, and ornamental Design for Chairs, of which the following is a specification, reference being had to the accompanying drawing, forming part thereof.

The figure is a perspective view of a chair showing my new design.

The novelty of the design resides in the ornamental effect of the frame construction and configuration as well as in the lines of beauty and effect of the arms and arm supports—especially to the curvature of the legs 1 rising from the rockers 2 and a further curvature of the back 3 terminating in the carved roll or scroll 4 at the

upper extremity of the back. Also in the curved legs 5 and the front portion 6 with the curved supporting members 7 for the arms 8 as well as in the scroll 9 intermediate the member 7. The arms 8 are provided upon their upper surfaces with carved scroll work 10 such arms extending vertically beyond the supporting member 7 and curved downwardly as at 11, such curved portion 11 being carved to represent feathers as at 13 and terminating in a head 14 and beak 15 of a conventional eagle or other bird.

I claim:

The ornamental design for a chair, as shown and described.

LORENZ KILLIAN.
